UNITED STATES PATENT OFFICE

2,553,247

COMPRESSOR

Everett E. Fowler, New York, N. Y.

Application November 19, 1946, Serial No. 710,812

1 Claim. (Cl. 230—160)

1

This invention relates to the art of refrigeration and more particularly to a compressor for use in small refrigeration plants, such for instance as used in household mechanical refrigerators.

It has for one of its objects a device in which no moving parts are located within the compression chamber, therefore no lubricant is required inside the chamber to coat the walls thereof with a film of insulation thereby materially reducing the efficiency of the device.

Another object is in the absence of reciprocating parts whereby noise is reduced to a minimum.

Another object is in the few parts comprising the structure, which lend to a reduction in cost of manufacture and assembly and further in the expense of maintenance and operation.

With these and other objects in view, the invention resides in the arrangement and combination of parts hereinafter described and particularly pointed out in the appended claim.

In the drawing:

Fig. 1 is a top plan view of the device.

Fig. 2 is a view in side elevation there being parts in section, the cutting plane of the section being indicated by the line 2—2 of Fig. 1.

Fig. 3 is a view in elevation taken at right angles to and enlarged over the showing in Fig. 2 there being parts broken away and other parts in section, the cutting plane being indicated at 3—3 of Fig. 1.

Referring to the drawings specifically by characters of reference the numeral 1 designates a base on which the component parts of the device are mounted. At 2 is shown a housing for suitable reduction gearing 3, comprising in the present instance a worm 4 mounted on a shaft 5, that receives motion from a motor 6, through a coupling 7. The worm 4 is in mesh with a gear wheel 8, mounted on a shaft 9. The shaft 9 extends from opposite sides of the housing 2 and has secured to each projecting end an eccentric 10, and the high point of each eccentric being located 180 degrees apart on the shaft 9.

Guide rods 11 are erected on the base 1 in pairs, each pair being connected at the top by a cross plate 12. Transverse brace bars 13 are secured, together with the cross plates 12 to the top of the upright rods 11 by nuts 14. A crosshead 15 is mounted for sliding movement on the guide rods 11. A roller 16 mounted on the under side of the cross head 15, overrides the face of the cam as shown.

2

The compressor unit 17 is of the bellows or accordion type, constructed of a series of flexible metal members hermetically sealed. Thus, even in the expanded position of the compressor unit, there is a high ratio of wall to cubic area. This ratio of course is heightened further during the compressed position of the unit. The bottom of the unit 17 rests on a resilient cushion 18 supported in a socket formed in the crosshead 15. The upper end of the compressor unit bears against the cross member 12 and is provided with inlet and exhaust ports 19 and 20 respectively. Each port is fitted with a check valve, diagrammatically illustrated at 21 and 22.

The cubical area of the compressor chamber 17 is further reduced by the introduction of a filler member 23 within the chamber, whereby reexpansion of gases on account of heat generated during compression is reduced to a minimum, with the filler member cooperating with the bellows wall to increase the above mentioned ratio.

Attention is called to the fact that by elongation of the shaft 9 any number of compressor units may be operated from a single source of power application.

What is claimed is:

In a compressor for refrigerating chambers a base; pairs of upstanding parallel guide posts 30 rigidly mounted at opposite sides of said base; fixed plates rigidly secured to the respective pairs, each plate being extended between the upper ends of the guide posts of a pair and being formed with a pair of oppositely check 35 valved openings extending therethrough, said openings respectively comprising an outlet and an inlet for refrigerant gases; spaced crossheads each having end openings through which the guide posts of a pair extend, said crossheads 40 being mounted for up and down sliding movement upon the guide posts; a pair of bellows each fixedly secured at its upper and lower ends respectively to a fixed plate and a crosshead, said check valved openings being in communication with the interior of said bellows; and means for imparting up and down reciprocating movement to said crossheads, said means being adapted to elevate one crosshead simultaneously with lowering of the other crosshead 45 for alternating compression of the respective bellows, thus to provide a substantially continuous flow of compressed refrigerant gases through said outlet openings, said means constituting a motor mounted upon said base; a 50 reducing gear box mounted on the base and

centered between the respective pairs of guide posts; an operative driving connection extending between the motor and said gear box; driven shafts extending out of the gear box laterally to positions under the respective bellows; eccentrics secured to the respective driven shafts, the high points of said eccentrics being spaced 180° apart; and rollers mounted upon the undersides of the crossheads and rollably engaged by the respective eccentrics.
